(57) **CLAIM**

The ornamental design for a “sock storage rack,” as shown and described.

DESCRIPTION

FIG. 1 is a front perspective view of the sock storage rack, showing my new design;

FIG. 2 is a rear perspective view of the sock storage rack;

FIG. 3 is a front elevational view thereof;

FIG. 4 is a rear elevational view thereof;

FIG. 5 is a side elevational view, the opposite side being a mirror image thereof;

FIG. 6 is a top plan view thereof; and,

FIG. 7 is a bottom plan view thereof.
